OIL FILTRATION SYSTEM

Charles W. McKinley, Flint, Mich., assignor to
A C Spark Plug Company, Flint, Mich., a company of Michigan

Application August 13, 1927, Serial No. 212,806

23 Claims. (Cl. 123—196)

This invention relates to internal combustion engines as used on automotive vehicles and has particular reference to a system of crankcase ventilation combined with an oil filter.

5 In the past crankcase ventilation systems have taken the air directly from the crankcase without causing it to pass through any intermediary device. It has also been the practice to construct the oiling system independent of the crankcase 10 ventilation. It is the purpose of the present invention to combine the two systems in order that the one may mutually aid the other.

Present day automotive engines are commonly provided with oil filters, and also with a crankcase 15 ventilating system designed to remove gasoline vapor and other diluents from the engine oil supply, but so far as I am aware the two systems have never been combined. It is the object of the 20 present invention to secure by the use of one apparatus the functions and advantages of both oil filtering and the vaporization of diluents.

The object of the invention is accomplished by 25 passing the air as it is drawn from the crankcase through the conventional oil filter. As the air passes through the filter it will come in contact with the filtered oil and carry along any water vapor or other impurity which is susceptible of 30 being taken up by the air. The stream of air drawn from the crankcase is rather warm and therefore assists in the vaporization of fluid diluents which may be found in the oil stream.

To attain the object of the invention I attach 35 to the intake manifold a pipe or connection which leads to the oil filter, and a second pipe or connection from the opposite end of the oil filter to the 40 crankcase. The connection from the filter to the crankcase permits the return of the filtered oil and at the same time serves as a passage for drawing the air in the crankcase through the filter. The flow of air will be in the reverse direction 45 to the flow of the oil and the amount of air passed through the connection is controlled by means of two valves. One of the valves is connected with the throttle so as to be operated simultaneously therewith and has two openings or 50 passages of different sizes. The second valve is spring pressed and may be placed at any suitable place in the system. I preferably place the spring 55 pressed valve so that it is between the filter and the throttle operated valve although the system will operate just as well if the spring pressed valve is arranged on the manifold side of the throttle operated valve. In actual practice both valves are placed between the filter and the intake man-

ifold, and it is the suction from the latter that operates the system.

The smaller opening of the valve connected to the throttle is used during starting or at relative low speeds and will permit but a relatively small portion of crankcase air to be drawn to the intake manifold. The size of the hole is so chosen that it does not interfere with the normal operation of the carburetor. The second hole in the valve is much larger, and when the car speed reaches about 15 miles per hour this hole begins to open and is fully opened at about 35 miles per hour car speed; or, in other words, when the throttle is fully open the larger opening is fully opened.

Experience has shown that this large opening and relatively large admission of air from the crankcase has no bad effect on the action of the carburetor at normal driving speeds. It has been found, however, that if the throttle is held wide open and the load increased on the engine until the car speed drops to 15 miles per hour or less the additional air entering the intake manifold through the large opening will reduce the carbureted mixture to such a degree that difficulty will be experienced in firing the mixture, and uneven

operation will result.

70

75

80

To remedy this condition of uneven operation caused by the relatively large admission of air through the larger opening when the engine is running at relatively low speeds, I provide the 85 spring pressed valve to which reference has previously been made. The pressure of the spring on the valve is so chosen that the valve will not be lifted at differences of pressure less than approximately three inches of mercury. This is 90 about the difference in pressure existing between the inside of the intake manifold and the atmosphere when the engine is developing its maximum horse power at maximum R. P. M. with the 95 throttle wide open.

If the R. P. M. of the engine is reduced while the throttle continues to be held wide open the difference between the pressure in the intake manifold and the atmosphere reduces progressively as the speed is reduced. As this difference in pressure becomes less, the spring pressed valve will tend to remain closed which will effect enriching of the carbureted mixture by closing the 100 ventilating connection through the filter.

105

In operation the device acts somewhat as an economizer in that a certain amount of fuel vapor which exists in the crankcase resulting from unconsumed gases that leak by the pistons is mixed with the air and redrawn into the firing chambers.

110

The invention is shown on the accompanying drawing in which:

Figure 1 shows the application of the structure of the invention to an internal combustion engine.

5 Figure 2 is an enlarged view of a portion of the structure of Figure 1 with parts shown in section.

Figure 3 is a sectional view on the line 3—3 of Figure 2.

10 Referring to the numbered parts on the drawing, 10 indicates an internal combustion engine, 12 the carburetor, 14 the intake manifold, 20 the oil filter, 16 the crankcase, and 18 the throttle valve. These parts are conventional and their structure per se forms no part of the invention.

15 The filter 20 has the usual inlet 21 and is connected at its lower end to the crankcase 16 as shown at 22, by means of a short length of pipe or tubing 24, and to the intake manifold 14 at its upper end by means of a connection 26 in the form of a tube or pipe which tapped as shown at 28 to the intake manifold.

20 The upper portion of the filter is provided with an opening 30 and over the opening there is applied a fitting 32 secured to the filter by means of the bolts 34. The lower portion of the fitting has an opening 33, concentric with the opening 30, while the upper portion is enlarged as shown at 36 to provide a chamber 38 in which there is housed a tapered coil spring 40, the apex of which presses against a one way valve 42. The seat of the valve is tapered to conform to the tapered seat 44, located at the junction of the neck portion 37 of the fitting 32 with the enlarged portion 36.

25 Secured to the fitting 32 is a housing 46 which incloses a valve 48 having a relatively small opening 50, and a relatively large opening 52 extending therethrough. The housing 46 has an opening 53 at its upper end, and an opening 54 at its lower end which communicates with the chamber 38 in the enlarged portion 36 of the fitting 32. The lower portion of the housing 46 is provided with a recessed portion as shown at 56 which recessed portion forms a continuation of the chamber 38.

30 Within the chamber 38 there is placed the conical-shaped member 58 having a seat 60 at its upper portion for the reception of the base of the tapering coil spring 40, while the apex of the conical member 58 is directed toward the stem 62, of the valve 42. The conical member 58 is provided with a plurality of openings 64 to allow for the passage of air through the openings 54, 50, 52, and 53, and to the tubing 26 which leads to the intake manifold 14. From an inspection of Figure 2 it will be apparent that the spring 40 is under compression and tends at all times to maintain the valve 42 on its seat 44.

35 The valve 48 has a stem 66 which extends outside the housing 56, and has attached thereto a lever 68 which is secured to the throttle lever 70 by means of an interconnecting link 72 the purpose of which is to cause the simultaneous operation of the throttle valve 18 with the valve 48.

40 From the position of the parts shown in Figure 2, it will be noted that the larger opening 52 of the valve 48 is just commencing to coincide with the openings 53 and 54 in the upper and lower portion of the housing 46, and at the same time the throttle valve 18 is commencing to open. When the levers 68 and 70 are further swung through an angle of approximately 80° the throttle valve 18 will be in wide open position while the opening 52 will be in alignment with the openings 53 and 54 in the housing 46 and allow

45 a free passage of the air through the connection 26 to the intake manifold. The position of the parts as shown in Figure 2 shows the operation of the engine at comparatively low speeds while when the valve 48 is so turned that the opening 52 is in alignment with the openings 53 and 54, the engine will be at its normal running speed, or will be under load at full throttle open position.

50 The openings 50 and 52 in the valve 48 are shown as at right angles to each other and may be so used but in actual practice I prefer to have them at an acute angle to each other; i. e., the angle between the openings at the opening 53 in Figure 2 will be less than 90°.

55 The passage of air through the system is caused by the suction in the intake manifold which at normal running speeds is sufficient to raise the valve 42 from its seat against the pressure of the spring 40. When the larger opening 52 is in alignment with the opening 54 and an increased load is added to the engine it will cause a decrease in the speed of the engine although the throttle valve 18 will be maintained in its full open position. In this situation the air which would be normally drawn through the opening 52 would be such as to seriously interfere with the efficiency of the mixture in the intake manifold and it is accordingly at this stage that the valve 42 closes the ventilation system entirely or 100 prevents the withdrawal of such quantity of air therethrough as will interfere with the efficient operation of the engine. The difference in the pressure in the intake manifold and in the atmosphere will be reduced progressively as the 105 speed is reduced; therefore, as the difference in pressure becomes less the spring pressed valve 42 will remain closed. The effect will be to enrich the carburetor mixture.

110 The flow of air in the system will be from the 115 crankcase 16 through the pipe 24, filter 20, fitting 32, valve housing 46, and connection 26 to the intake manifold and is in reverse direction to the flow of filtered oil. The oil will enter the filter at the inlet 21, pass through the filtering 120 material 27, and flow to the crankcase through the outlet pipe 24 (the remaining portion of the filtering system is not shown or described as it is of the conventional kind and per se forms no part of the invention except insofar as it enters 125 into combination with the remainder of the structure). Because of the reverse flow of the air and oil, and due to its heated condition, the air will absorb or carry along therewith water vapor or other impurities or diluents in the oil and deliver 130 them to the firing chamber, resulting in a purifying of the oil.

I claim:

1. In combination with an internal combustion engine and an oil filter, a system of crankcase ventilation operated from the suction of the intake manifold comprising a connection between the crankcase and manifold passing through the filter casing, means in the connection for controlling the passage of air through the connection including a member having a plurality of different sized openings, said member being connected to the engine throttle in such a manner that the larger opening will be in alignment with the connection during throttle open position only.

140 2. In combination with an internal combustion engine and an oil filter, a system of crankcase ventilation operated from the suction of the intake manifold comprising a connection between the crankcase and manifold passing through the

- filter, means having a plurality of different sized openings and operated simultaneously with the engine throttle for regulating the flow of air through the connection, said smaller opening being in alignment with the connection during throttle closed position only. 80
3. The combination of an engine having a lubricating system and a crankcase, an oil filter, means for passing oil from the system to the filter and returning the filtered oil to the crankcase, and means for causing air from the crankcase to pass through the filter to come into contact with the filtered oil in the filter for removing diluents therefrom. 85
15. 4. The combination of an engine having a circulating lubricating system and a crankcase, an oil filter, means for conducting oil from said system to said filter, a conduit for leading filtered oil from said filter to the crankcase, and means for causing a flow of air through said conduit and through the filter in contact with the filtered oil for effecting removal of diluents. 90
20. 5. The combination of an engine having a circulating lubricating system and a crankcase, an oil filter, a casing for said filter, means for conducting oil from said system to said filter, a conduit for returning filtered oil from said casing to the crankcase, and means for drawing air through said conduit and entirely through said casing in contact with said stream of filtered oil for effecting removal of diluents. 95
25. 6. In combination with an internal combustion engine and an oil filter, a system of crankcase ventilation including a connection between the crankcase and the intake manifold passing through the oil filter casing, to draw the air from the crankcase through the filter in direct contact with the oil therein. 100
30. 7. In combination with an internal combustion engine and an oil filter, a system of crankcase ventilation including a connection between the crankcase and the intake manifold passing through the oil filter casing to draw the air from the crankcase through the filter in direct contact with the oil therein, and means operated with the engine throttle for regulating the flow of air. 110
35. 8. In combination with an internal combustion engine and an oil filter, a system of crankcase ventilation including a connection between the crankcase and the intake manifold passing through the oil filter casing to draw the air from the crankcase through the filter in direct contact with the oil therein, and means in the connection between the filter and manifold and operated with the engine throttle for regulating the flow of air therethrough. 115
40. 9. In combination with an internal combustion engine and an oil filter, a system of crankcase ventilation including a connection between the crankcase and the intake manifold passing through the oil filter casing to draw the air from the crankcase through the filter in direct contact with the oil therein, and a valve in said connection having a plurality of openings for regulating the flow of air therethrough. 120
45. 10. In combination with an internal combustion engine and an oil filter, a system of crankcase ventilation including a connection between the crankcase and the intake manifold passing through the oil filter casing to draw the air from the crankcase through the filter in direct contact with the oil therein, and a valve in said connection having a plurality of openings of different size for regulating the flow of air therethrough. 125
50. 11. In combination with an internal combustion engine and an oil filter, a system of crankcase ventilation including a connection between the crankcase and the intake manifold passing through the oil filter casing to draw the air from the crankcase through the filter in direct contact with the oil therein, and a plurality of valves for regulating the flow of air through the connection. 130
55. 12. In combination with an internal combustion engine and an oil filter, a system of crankcase ventilation including a connection between the crankcase and the intake manifold passing through the oil filter casing to draw the air from the crankcase through the filter in direct contact with the oil therein, and a plurality of valves for regulating the flow of air through the connection, one valve operated manually and the second valve spring operated. 135
60. 13. In combination with an internal combustion engine and an oil filter, a system of crankcase ventilation including a connection between the crankcase and the intake manifold passing through the oil filter casing to draw the air from the crankcase through the filter in direct contact with the oil therein, and a plurality of valves for regulating the flow of air in the connection, one of said valves operated manually with the engine throttle. 140
65. 14. In combination with an internal combustion engine and an oil filter, a system of crankcase ventilation including a connection between the crankcase and the intake manifold passing through the oil filter casing to draw the air from the crankcase through the filter in direct contact with the oil therein, and means for controlling the flow of air through the connection comprising a spring operated valve, a second valve adjacent said spring operated valve, a plurality of passages in said second valve, and a connection between said second valve and the engine throttle whereby said valve is operated simultaneously with the throttle. 145
70. 15. The combination of an engine having a circulating lubricating system and a crankcase, an oil filter, means for conducting oil from said system to said filter, a conduit for leading filtered oil from said filter to the crankcase, and means for causing a flow of air through said conduit and through said filter in contact with said stream of filtered oil for effecting removal of diluents, said air flowing in a direction opposite to the direction of flow of the stream of oil. 150
75. 16. In a system of crankcase ventilation for internal combustion engines in combination with an oil filter in the engine lubricating system, and means for drawing air from the crankcase through the oil filter in direct contact with the oil therein. 155
80. 17. In combination with an internal combustion engine and an oil filter, a system of crankcase ventilation including a flow connection between the crankcase and the intake manifold passing through the oil filter casing to draw the air from the crankcase through the filter in direct contact with the oil therein, and means in the connection to regulate the flow of air therethrough. 160
85. 18. In combination with an internal combustion engine and an oil filter, a system of crankcase ventilation including a connection between the crankcase and the intake manifold passing through the oil filter casing to draw the air from the crankcase through the filter in direct contact with the oil therein, and means in the con- 165

nection between the filter and manifold for regulating the flow of air therethrough.

19. In combination with an internal combustion engine and an oil filter, a system of crankcase ventilation including a connection between the crankcase and the intake manifold passing through the oil filter casing to draw the air from the crankcase through the filter in direct contact with the oil therein, and a valve in said connection for regulating the flow of air therethrough.

20. In a system of crankcase ventilation for internal combustion engines having a lubricating system, in combination with an oil filter, a suction operated means for drawing air and vapor from the crankcase through the oil filter in direct contact with the oil therein.

21. In combination with a system of crankcase ventilation for internal combustion engines

20

having a lubricating system including an oil filter, means for passing air from the crankcase through the body of oil in the oil filter.

22. In combination with a system of crankcase ventilation for internal combustion engines having a lubricating system including an oil filter, means for passing air from the engine crankcase in contact with the oil after it has been filtered and then passing said air through the body of oil in the oil filter.

23. In combination with a system of crankcase ventilation for internal combustion engines having a lubricating system including an oil filter, means for passing air from the engine crankcase into contact with the oil after it has been filtered and then passing said air into contact with the oil while it is being filtered.
